TEMPERATURE CONTROL SWITCH

John P. Buller, Ringwood, Okla.

Application March 28, 1940, Serial No. 326,512

2 Claims. (Cl. 200—138)

My invention relates to improvements in selective automatic thermostatic controls for electric refrigerators, and the primary object of the invention is to provide an arrangement of this character whereby the temperature within the refrigerator will remain constant at the selected temperature despite variation of temperature outside of the refrigerator, and wherein the box temperature is regulated and controlled without requiring turning up the pressure during the day and turning the pressure down during the night.

Other important objects and advantages of my invention will be apparent from a reading of the following description taken in connection with the drawings, wherein for purposes of illustration I have shown a preferred embodiment of my invention.

In the drawings:

Figure 1 is a general schematic view showing an arrangement in accordance with the present invention applied to a conventional electrical refrigerator.

Figure 2 is an enlarged front elevational view of the mechanical type of thermometer switch with attendant electrical connections and the sliding temperature selecting switch.

Figure 3 is a fragmentary transverse vertical sectional view taken through Figure 2 approximately on the line 3—3 and looking toward the left in the direction of the arrow.

Figure 4 is a fragmentary top plan view of the sliding selective switch.

Figure 5 is a fragmentary view of another thermometer control switch arrangement which can be substituted for that shown in Figure 2 of the drawings.

Referring in detail to the drawings, the numeral 5 generally designates a conventional type of electrical refrigerator which includes within its interior 6 the refrigerating unit 7 which in accordance with the present invention has mounted in a suitably visible place thereon the thermometer switch which is generally designated 8 from which lead respective conduits 9 and 10 enclosing conductors leading to opposite sides of the current supply 11. If desired a reducing transformer 12 may be inserted in one side of the circuit, preferably in the wire 13 in the conduit 10. The conduit 9 contains the wire 14 which leads to the opposite side of the supply circuit and has connected therein the sliding selector switch which is generally designated 15.

The sliding switch 15 comprises a preferably 55

vertically elongated dielectric body 16 which is L-shaped in cross section as indicated in Figure 4 with the plate portion 17 provided on its exposed face with vertically spaced numerals 18 designating different degrees of temperature. The adjacent face 19 on the main portion of the body 16 has vertically spaced contacts 20 positioned in alignment with the numerals 18, and for selectively bridging these contacts 20 there is provided the C-shaped slider 21 whose laterally inwardly turned flanges 22 engage in conforming vertical slots 23 in the opposite sides of the body 16 as clearly shown in Figure 4, with the right angle flange adjacent the plate 17 engaging the contacts 20. The slider 21 is of sufficient length so that when pushed to its extreme depressed position it will engage and bridge all of the contacts 20. The body portion 16 is sufficiently vertically elongated so that the slider 21 can slide upwardly a sufficient distance to engage only the uppermost of the contacts 20. The current supply wire 14 is connected to the slider 21 as indicated in Figure 1, while the wires 14', of which one leads from each of the contacts 20, are contained in the conduit 8 and lead to corresponding contacts 24 which are arranged in an arcuately spaced series on a dielectric block 25 mounted on a partition 26 extending across the cylindrical casing of the thermometer switch 8, with the conduit 8 leading into the rear part of the said casing and distributing its individual wires 14' through appropriate openings 27 in the partition 26. A conductive pointer 28 is fixed to an axle or shaft 29 so as to extend in front of the series of contacts 24 as indicated in Figure 3 and make selective engagement with any one of the said contacts in accordance with the positioning which is imparted to the axle 29 by the thermo-responsive mechanism 30 behind the partition 26, the mechanism 30 being of any suitable conventional type. A suitable glass 31 is mounted in front of the pointer and secured in the casing so as to expose the position of the pointer 28 to view while the door 32 of the refrigerator 5 is in an open position.

Referring now to the form of thermometer switch illustrated in Figure 5 of the drawings which may be substituted optionally for that shown in Figure 2, there is involved a glass or other suitable material thermometer tube 31a through which the mercury 28a may be seen as it rises and falls due to temperature change. At one side of the thermometer tube is mounted a plate 17a having temperature degree designa-

ations 18a thereon and at the opposite side of the thermometer tube and exposed within the bore thereof are vertically spaced contacts 20a corresponding in position to the designations 18a. The wires 14' which lead to the slider equipped selector switch 15 are connected to the contacts 20a similar to the contacts 20 of the first described embodiment. It is obvious that as the mercury 28a rises and falls within the thermometer tube 31a that the various contacts 20a below the uppermost reach of the mercury will be bridged by the mercury. In the case of the last described embodiment the connections of the wires 14' with the contacts 20 will be exactly the reverse of the connection of the contacts 20 with the contacts 24, because of the inverted relationship of the progress of the elements which bridge the contacts 20a and 20, respectively.

In the case of the first described embodiment the wire 14 is the wire which completes the circuit between the control of the present invention and the refrigerator unit 7, while in the case of the second described embodiment the wire 14b connected to the mercury 28 below the contacts 20a is the wire which carries the current from the line to the control.

Each contact point 24 of the thermometer switch 8 corresponds to a certain degree of temperature and is connected by its corresponding individual wire 14' with its companion contact point 20 of the slide switch 15. The contacts 20a of the mercury type thermometer switch 8a are connected in the same way. The pointer 28 of the thermometer switch 8 is connected to one side of the current source 11, while the sliding contactor of the switch 15 is connected to the electric motor driving the compressor. Therefore, when the air within the refrigerator compartment reaches the temperature set on the switch 15 and the pointer 28 on the thermometer switch 8 is thereby caused to engage the corresponding one of its contacts 24, the current supply goes through the two switches to the compressor motor so as to operate the compressor until the temperature in the refrigerator compartment is lowered sufficiently to permit the pointer 28 to move off the described contact and thereby break the motor circuit.

The same essential actions take place in an installation wherein the mercury type thermometer switch 8a is used in place of the pointer switch 8.

It will be observed that it is characteristic of the construction of the slide switch 15 that all of its contact points 20 above that corresponding to that of the set temperature are contacted by the slide. This arrangement is provided so that the operation of the compressor for the described reduction of box temperature will take place and continue even though that temperature should temporarily go substantially above the temperature for which the slide switch has been set, thereby assuring the necessary reduction in temperature.

When using the pointer thermometer switch 8 the lead to the compressor motor should be divided and one terminal connected to the slider 21 of the slide switch 15 and the other terminal to the pointer 28. When using the mercury type thermometer switch 8a, the motor lead should be similarly cut and one terminal connected to slider 21 of the slide switch 15 and the other terminal

connected to the electrode of the mercury bulb, so that the current will flow through the mercury switch and the slide switch to the motor.

Although I have shown and described herein preferred embodiments of my invention, it is to be definitely understood that I do not wish to limit the invention to the precise forms and arrangements shown and described, except as may be required by the scope of the subjoined claims.

Having described the invention, what is claimed as new is:

1. A switch in an electric circuit comprising a non-conductive, elongated, stationary body and a conductive selector member slidably mounted thereon; said body being L-shaped and provided on both opposite flat sides with longitudinal slots and on one of said sides with a flat lateral plate, a series of longitudinally spaced contact points on said body adjacent said flat plate having a corresponding graduation, said selector member being U-shaped and having inwardly projecting flanges engaging in said slots and bearing against said contact points, the selector member being longitudinally adjustable along said body to selectively engage one or all of said contact points, and a conductive pointer adapted for marking the temperature produced, a thermoresponsive mechanism adapted for positioning said pointer, a series of spaced, arcuately arranged contact points in a dielectric block with corresponding graduation making for cooperating with said pointer, individual leads connecting corresponding contact points on said body with the contact points in said arcuate block, a conductor between said selector member and one pole in the electric circuit and another conductor from said pointer to the other pole of said circuit.

2. A switch in an electric circuit comprising a non-conductive, elongated, stationary body and a conductive selector member slidably mounted thereon; said body being L-shaped and provided on both opposite flat sides with longitudinal slots and on one of said sides with a flat lateral plate, a series of longitudinally spaced contact points on said body adjacent said flat plate having a corresponding graduation, said selector member being U-shaped and having inwardly projecting flanges engaging in said slots and bearing against said contact points, the selector member being longitudinally adjustable along said body to selectively engage one or all of said contact points, and a conductive pointer adapted for marking the temperature produced, a thermoresponsive mechanism adapted for positioning said pointer, a series of spaced, arcuately arranged contact points in a dielectric block with corresponding graduation marking for cooperating with said pointer, individual leads connecting corresponding contact points on said body with the contact points in said arcuate block, a conductor between said selector member and one pole in the electric circuit and another conductor from said pointer to the other pole of said circuit, said selector member being sufficiently long to engage all of the contact points in one extreme position and said body being sufficiently long to enable said selector member to be selectively adjusted on said body to the opposite extreme position or any intermediate position in which said selector member engages only the adjacent end contact point of said series of contact points.

JOHN P. BULLER.
